[57] CLAIM

The ornamental design for a bathroom handle or the like, as shown and described.

DESCRIPTION

FIG. 1 is a perspective view of a bathroom handle or the like showing our new design;

FIG. 2 is a top plan view thereof;

FIG. 3 is a right side elevational view thereof;

FIG. 4 is a left side elevational view thereof; and

FIG. 5 is a front elevational view thereof, the rear being a mirror image of the front shown.

The fragmentary broken line showing of a pipe in FIG. 1 is for purposes of illustration only.
